(57) CLAIM

The ornamental design for a surface cleaner base, as shown and described.

DESCRIPTION

FIG. 1 is a front, right perspective view of a surface cleaner base showing my new design;

FIG. 2 is a front view thereof;

FIG. 3 is a right side view thereof;

FIG. 4 is a left side view thereof; and,

FIG. 5 is a top view thereof.

The details shown in broken lines form no part of the claimed design.

1 Claim, 5 Drawing Sheets

FIG. 1

FIG. 2

FIG. 3

FIG. 4

FIG. 5
